UNITED STATES PATENT OFFICE.

CHARLES D. GOLDEN, OF CHICAGO, ILLINOIS.

DESIGN FOR A CLOCK-CASE.

SPECIFICATION forming part of Design No. 26,670, dated February 23, 1897.

Application filed January 16, 1897. Serial No. 619,493. Term of patent 3½ years.

To all whom it may concern:

Be it known that I, CHARLES D. GOLDEN, a citizen of the United States, residing at Chicago, in the county of Cook and State of Illinois, have invented and produced a new and original Design for Clock-Cases, of which the following is a specification, reference being had to the accompanying drawing, embodied in a single figure, showing a front elevation in relief of a clock-case illustrating my design.

The principal feature of my design consists in the representation in relief of the landing of a ship, upon which is represented the figure of Columbus in a prominent position, and at his side a ship's sail with the clock-face as its central feature.

Referring to the drawing, *a* represents a Spanish caravel in relief supported upon waves forming the base of the structure represented in my design. Upon the left in the immediate foreground is represented the crouching and prostrate figures of natives, together with trees and foliage. Above the bow of the ship is represented a globe *b*, sur-

mounted by an eagle with outstretched wings 25 and flanked upon each side by a group of flags. A figure of Columbus in armor is represented as standing upon the deck of the vessel amid packages of merchandise, while at his right and partially behind him is a large 30 sail *c*, supported by yard-arms *d e*, the former of which is suspended by means of cordage *f*, secured to the mast *g*. A streamer *h* is gracefully festooned and intertwined with the cordage, which depends in loops and tassels from the ends of the yard-arm. A circular clock-face *i*, surrounded by a beaded border, forms the central feature of the sail. 35

I claim—

The design for a clock-case, substantially 40 as shown and described.

In testimony whereof I have signed this specification, in the presence of two subscribing witnesses, this 23d day of December, 1896.

CHARLES D. GOLDEN.
